E. J. WILSON

METHOD AND MACHINE FOR TREATING FELTS

Filed March 20, 1922

UNITED STATES PATENT OFFICE.

EZEKIEL J. WILSON, OF EAST GREENBUSH, NEW YORK, ASSIGNOR TO F. C. HUYCK & SONS, OF RENSSELAER, NEW YORK, A CORPORATION OF NEW YORK.

METHOD AND MACHINE FOR TREATING FELTS.

Application filed March 20, 1922. Serial No. 545,262.

To all whom it may concern:

Be it known that I, EZEKIEL J. WILSON, a citizen of the United States, residing at East Greenbush, in the county of Rensselaer and State of New York, have invented certain new and useful Improvements in Methods and Machines for Treating Felts; and I do hereby declare the following to be a full, clear, and exact description of the invention, such as will enable others skilled in the art to which it appertains to make and use the same.

The invention relates to a method of treating felts such as are used in paper machines, and to a machine for subjecting felts to such treatment.

In manufacturing felts for paper machines the felts after being fabricated and fulled are subjected to a stretching and drying operation by which the felt is brought to the finished length requisite for its subsequent use. During its subsequent use in a paper machine the felt in a wet condition is operated under heavy tension and its value and efficiency is dependent upon its capacity to continue taut and flat under this heavy tension without requiring frequent or excessive adjustment of the tension rolls of the machine and the consequent reduction in the quality or quantity of production. It is of vital importance, therefore, to the proper operation of the felt when put to its intended use that the tension to which it is subjected during the stretching and drying should be sufficiently in excess of that to which it will be subjected in the paper machine to insure its successfully resisting the heavy stretching tension under which it operates. It is likewise important that the tension applied to the felt in the stretching and drying operation should be well within that which the felt is designed to withstand as otherwise the felt may be permanently strained or rendered defective although the defect may become apparent only under the conditions of subsequent use.

The present invention insures the production of felts which have uniformly been fabricated and treated to satisfactorily and efficiently meet the conditions under which they are to be used and this is accomplished by subjecting the fulled felt to a measured tension in stretching it to its finished length

during the drying and finishing operation. If, in stretching and drying a felt, the measured tension to which it is being subjected approaches the limit which the felt is designed to withstand, or if when stretched to finished length the tension which has been applied to the felt is below that requisite for meeting the operating requirements of the felt, it may be discarded or it may be re-treated and again dried and stretched to length under a measured tension which is appropriate to the use for which the felt is designed and well below that which the felt is designed to withstand. The production of felts which have uniformly been properly fabricated and treated to properly meet the requirements of their subsequent use is thus insured or rendered practicable. This enables the manufacturer to put upon the market a standardized product which can be relied upon to stand up and efficiently effect its function in the paper machine under all normal operation conditions. This is not only of great practical importance and value to the manufacturer of felts but is also of equal importance to the user of the felts since it avoids the expense and loss of production incident to the use of a felt which has not been properly fabricated and treated.

In manufacturing felts by the method of the present invention the felt is fabricated by weaving or by weaving and splicing in such manner that an endless web is formed which is considerably longer than the length which the finished felt is to have. The felt is then fulled to a length considerably less than its finished length and is then stretched to a pre-determined finished length under a measured tension while being dried and finished. The stretching to a pre-determined length under measured tension during the drying and finishing may be effected in an efficient manner by mechanism which also forms a part of the invention. A preferred form of this mechanism is embodied in the felt drying machine to which reference will be made in the further description of the invention.

This machine is shown in the accompanying drawings in which Fig. 1 is a side elevation showing so much of the machine as is necessary to illustrate the present inven-

tion, and Fig. 2 is a detailed plan view of the tension measuring links through which the take-up or tensioning roll is operated.

After the felt has been fabricated and fulled in the manner above described it is taken to the drying machine indicated in the drawings where it is subjected to a measured tension in stretching it to finished length during the drying. The machine illustrated 10 comprises a heated drying cylinder 2 which is mounted and driven in the usual manner and a take-up or tensioning roll 4 over which the felt 6 passes and by movement of which the damp and unfinished felt 15 is stretched to its final length. The take-up roll is mounted in bearing blocks 8 arranged at opposite ends of the roll and supported and guided on the fore and aft guide bars 10.

20 The mechanism for operating the take-up roll to subject the felt to a measured tension in stretching it to finished length during the drying comprises two blocks 12 mounted for movement on the guide bars 10 and connected with the bearing blocks 8 by tension measuring links 14 through which the felt stretching pull is applied to the take-up roll. As shown each tension measuring link comprises an elliptical shaped loop, one end of 25 which engages a pin 16 on the bearing block 8 and the other end of which engages a pin 18 on the block 12. When the blocks 12 are actuated to draw the bearing blocks 8 and take up roll forcibly away from the drying 30 drum 2 and thus stretch the felt, the pull which is transmitted through the links 14, causes the opposite sides of each link to be drawn toward each other, the relative movement between the sides being proportional 35 to the pull transmitted through the link. This pull is measured and indicated in pounds by pointers 20 and 22 which are caused to move over a calibrated scale 24 by the relative movement between the sides of 40 the link. The scale 24 is formed on a plate 26 secured to one of the sides of the link and the pointer 20 is carried by a shaft 28 mounted on the plate and provided with a pinion engaging a rack 30 secured to the 45 opposite side of the link. The pointer 22 is so connected to the shaft 28 that it will move with the pointer 20 as the sides of the link gradually contract or approach each other under an increasing pull applied thereto but will be unaffected by the return movement of the sides of the link which moves the pointer 20 in a reverse direction. The 50 pointers 22 will, therefore, measure and indicate in pounds the maximum pull which has been transmitted through the links in 55 acting upon any felt, while the pointer 20 will measure and indicate in pounds at the end of the drying operation the tension under which the drying of the felt is completed.

Any suitable mechanism may be utilized for moving the blocks 12 along the guide bars 10 to operate the take-up roll. As indicated the blocks are moved on the guide bars by pinions 32 carried on a transverse shaft 34 and engaging racks 36 on the guide bars. The shaft is provided with a worm wheel 38 which is engaged by a worm 40 on a shaft 42 driven from a reversible electric motor 44. The motor may be started, stopped or reversed by the operator and the worm and worm wheel act to lock the blocks 12 and take-up roll 4 in any position into which they are moved by the power transmitted from the motor. The motor and driving connections may be mounted on a carriage provided with bearings engaging the shaft 34 so that the carriage will travel with the shaft.

80 In the use of the machine the damp fulled felt is applied to the drying cylinder and take-up roll, and the roll is then drawn away from the cylinder to stretch the felt as it travels over the cylinder and roll, the felt being stretched to a pre-determined length before it is completely dried and finished. As the stretching of the felt progresses the pointers on the tension measuring links through which the pull is transmitted to the take-up roll measure and indicate to the operator the tension which is being applied to the felt. After the felt has been stretched to the required length the drying is completed with the take-up roll in this position and the tension on the felt, if it has been properly fabricated and treated, should be somewhat less at the completion of the drying and finishing operation than the maximum tension required to stretch the damp or partially dried felt to its finished length. The pointer 20 at the completion of the drying and finishing will indicate the tension on the felt at this point in the operation, while the pointer 22 will indicate the maximum tension to which the damp or partially dried felt was subjected in stretching it to the required length. The tension or strain under which each felt is brought to finished length while still damp and which it is adapted to withstand without material stretching when subsequently put in use in a paper machine is thus measured by the machine so that the production of felts which may be depended on to operate in a uniform and efficient manner is rendered practicable. The extent to which the tension is relieved by the final drying of the felt is also indicated and this as well as the maximum tension may be recorded for future reference as occasion may require.

110 What is claimed is:

1. In the making of felts for paper making machines by the method which includes fabricating the felt in the form of an endless web having a length materially greater

than the finished felt, fulling the felt to a length materially less than the finished felt and drying and stretching the fullled felt to the finished length; the method of testing the felt by measuring the tension applied thereto during the stretching and drying.

2. In the making of felts for paper making machines by the method which includes 10 drying the damp fullled endless felt and stretching it to a pre-determined length before the drying is completed; the method of testing the felt by measuring the tension applied thereto during the stretching and 15 drying and indicating the maximum ten-

sion applied during the stretching and drying and also the tension applied at the completion of the drying.

3. In a machine for drying and stretching to its finished length a felt for paper making machines which has been fullled to a materially less length, the combination with the drying cylinder, take-up roll and mechanism for drawing the roll away from the cylinder, of tension measuring links connecting said mechanism with said take-up roll, and means acting during the stretching and drying to indicate the pull transmitted through each link to the take-up roll.

EZEKIEL J. WILSON.
